POISING AND BALANCING TOOL

William E. Berlincourt, Montreal, Quebec, Canada

Application October 6, 1947, Serial No. 778,129

4 Claims.

(Cl. 73—66)

1

This invention relates to tools used in the making and repairing of instruments and particularly to poising and balancing tools.

One of the objects of the invention is to provide a poising and balancing tool which can be quickly set up for use without the necessity of using levels and other adjusting mechanism.

A further object is to provide a poising and balancing tool which is self levelling and ready for use on any common work bench.

A further object is to provide a poising and balancing tool which is adaptable to a wide variety of uses without the necessity of changing parts and adjustment of setting.

A further object is to provide a poising and balancing tool which is of simple and compact construction, cheap to manufacture and requires little maintenance and upkeep.

These and other objects will be apparent from the specification and drawings illustrating the invention.

In the drawings,

Figure 1 is a perspective view of the device.

Figure 2 is a perspective view of one of the knife edge blocks.

Figure 3 is a face view of the block illustrated in Figure 2.

Figure 4 is a perspective view of the weighted pivot bar.

Figure 5 is a view showing one of the adjustment screws.

Referring to the drawings, the pivot ring 10 is provided with two drilled holes 11, diametrically opposite each other. These holes 11 act as journal bearings for the pins 12 which project from the main supporting frame 13. The frame 13 may be of any convenient form and requires no means for adjusting for level, the only requirement being that the pins 12 be reasonably level with the base of the frame 13.

A pair of pivot pins 14 are threaded into the pivot ring 10, diametrically opposite each other and at right angles to the pins 12. The pins 14 are pointed at 15 to provide fine pivot bearing points and are preferably hardened.

The swing bar 16 is provided with a pair of conical shaped holes 16a at a point midway of the length of the bar and on opposite sides. These holes 16a are of slightly wider taper than that on the ends of the pivot pins 14 in order to reduce to a minimum the friction of the pins 14 when adjusted to fit into the bearing holes 16a. A shaft 17 is fixed to the swing bar 16 midway of its length and at right angles thereto. A weighted sphere 18 is securely fixed to the lower end of

the shaft 17. The sphere 18 can be a ball bearing or such like article and be of such mass, considering the weight and disposition of the other parts of the mechanism, as to hold the pivoted parts in balanced and level position. The ends of the swing bar 16 are shown as having flats 19. However the ends could be squared or of any other shape if required.

A pair of knife edge blocks 20 have the apertures 21 at their lower ends. These apertures 21 are shaped the same as the ends 19 of the swing bar 16 and allow for sliding of the blocks 20 on the bar 16 but prevent the blocks from rotating thereon. Adjustment bars 22 are fixed in the blocks 20, one to each block. The adjustment bar 22 of one block is guided in the aperture 23 of the opposite block, the ends of the bars being threaded at 24 to take the adjusting nuts 25.

A spring 26 fits around the swing bar 16 with an equal number of turns disposed on either side of the shaft 17. Alternatively, two springs of equal capacity can be fitted, one on either side of the shaft 17. The outer ends of the spring 26 seat in the counterbores 28 of the blocks 20, which, together with the recessed face 30 of the blocks, allows the main faces of the blocks to come together when so adjusted by the adjusting bars 22 and adjusting nuts 25.

The top ends of the blocks 20 are tapered to provide a knife edge at 27. These edges are machined accurately parallel and at right angles to the shaft 17 carrying the spherical weight 18. The edges 27 are preferably hardened.

The blocks 20 are cut away on either side at 29 to give maximum clearance for the ring 10 in extreme displaced positions of the mechanism.

In the operation of this invention, the support frame 13 is of suitable design and weight to hold the mechanism stable under all working conditions. The pivot pins 12 supported by the frame 13 need only be reasonably level as the device itself will seek its own level. As the weighted assembly of the blocks 20 is pivoted on the pins 14 and the ring 10 is pivoted on the pins 12, the device is therefore free to swing in any direction within the limits of clearance designed for. The spherical weight 18 is sufficiently heavy as to hold the blocks 20 and therefore their knife edges 27 steady and in a level position regardless of the level of the frame 13. It is understood that the bench on which the operator is working will be reasonably level and therefore the degree of out of level of the frame 13 will be very little.

With the edges 27 always level and the weight

18 being sufficiently great to hold these edges level while applying the work that is to be checked, very little skill is required in the use of the device. No time need be taken up in adjusting and levelling the device preparatory to doing the actual work.

In applying work to the device, the relative spacing of the blocks 20 from each other is adjusted by means of the threaded nuts 25. As the springs 26 are equally disposed on the swing bar 15 adjustment of one or both nuts 25 will effect equal movement of the blocks 20 relative to the centre of gravity of the device through the weight 18.

While the work to be balanced is being placed on the knife edges of the device, a slight degree of movement may take place, but this movement is quickly stabilized as soon as the hand is removed. Any such movement can be eliminated by reasonably skilled operators.

Due to the fact that the faces of the blocks 20 can be adjusted to touch each other by having the spring ends seated in the counterbores 28, it is possible to use this device as a vise for particular forms of work, thereby greatly increasing its usefulness.

In Figure 4 of the drawings, the weight 18 is shown flattened at 31. By using such a flattened weight and where the work bench is particularly level, it is possible to use the device without the ring 10 and the base 13, as the weight alone would hold the device steady and level. Again, it is possible to use the device without the base 13 as shown in Figure 1, and substitute therefore a staking tool as commonly used in instrument repair. The pins of the staking tool substituting for the pins 12.

Generally, in the repair and maintenance of instruments, particularly where there is a large volume of a variety of work and the time available for doing the work is limited, it has been found too costly to carry out any balancing of parts, and has been undertaken only under the heading of major repairs. This has been found to be due mainly to the time taken in settling up and levelling the devices hitherto in use for this class of work. This is particularly the case where a large variety of types and sizes are involved, in addition to the high first cost of such devices. This condition has been found to be particularly true in the watch repair industry, where a large volume of work has to be done within a limited time and relatively low cost is an essential. The device herein described provides the operator with a sturdy, cheap and efficient device of relatively non-precision manufacture, which can be adjusted to take various sized elements in a minimum of time and effort.

While a particular form of the device has been described and illustrated, it will be readily seen that the various elements making up the device could be changed in form and design without departing from the scope of the invention.

What I claim is:

1. In a poising and balancing tool, a swing bar, a weight rigidly suspended from said swing bar, a pair of blocks slidably mounted on said swing

bar, each of said blocks having knife edges at the top, parallel with each other and held level by said suspended weight, means to adjust said blocks on the swing bar relative to each other, spring means holding said blocks apart against said adjusting means, a pivot ring, pivot pins projecting inwardly from said ring to support said swing bar, and pivot means supporting said pivot ring at right angles to the pivot pins supporting the swing bar.

2. In a poising and balancing tool, a swing bar, a weight rigidly suspended from said swing bar, a pair of blocks slidably mounted on said swing bar one on either side of the support point of said weight, said blocks being recessed on their inward faces to allow them to contact each other above the swing bar and having knife edges at the top, parallel with each other and held level by said suspended weight, a pivot ring, pivot pins projecting inwardly from said ring to support said swing bar, and pivot means supporting said pivot ring at right angles to the pivot pins supporting the swing bar.

3. In a poising and balancing tool, a swing bar, a weight rigidly suspended from said swing bar, a pair of blocks slidably mounted on said swing bar one on either side of the support point of said weight, said blocks being recessed on their inward faces to allow them to contact each other above the swing bar and having knife edges at the top, parallel with each other and held level by said suspended weight, spring means holding said blocks apart, means to adjust the position of said blocks on the swing bar relative to each other against the pressure of said spring means, a pivot ring, pivot pins projecting inwardly from said ring to support said swing bar, and pivot means supporting said pivot ring at right angles to the pivot pins supporting the swing bar.

4. In a poising and balancing tool, a swing bar, a weight rigidly suspended from said swing bar, a pair of blocks slidably mounted on said swing bar one on either side of the support point of said weight, said blocks being recessed on their inward faces to allow them to contact each other above the swing bar and having knife edges at the top, parallel with each other and held level by said suspended weight, spring means holding said blocks apart, means to adjust the position of said blocks on the swing bar relative to each other equally on either side of the centre of gravity against the pressure of said spring means, a pivot ring, pivot pins projecting inwardly from said ring to support said swing bar, and pivot means supporting said pivot ring at right angles to the pivot pins supporting the swing bar.
